CLAIM

The ornamental design for a telephone handset, as shown and described.

DESCRIPTION

FIG. 1 is a left side elevational view of a telephone handset showing my new design;

FIG. 2 is a front elevational view thereof;

FIG. 3 is a top plan view thereof;

FIG. 4 is right side elevational view thereof;

FIG. 5 is a rear elevational view thereof;

FIG. 6 is a bottom plan view thereof; and

FIG. 7 is a perspective view thereof.

The showing of an electric cord in abbreviated form in the sundry figures is for facility of illustration.
